UNITED STATES PATENT OFFICE.

STERNE MORSE, OF CLEVELAND HEIGHTS, OHIO.

ELECTRIC HEATER.

Application filed February 6, 1926. Serial No. 86,413.

- This invention relates to electric heating units, and particularly to an electric heater unit adapted to maintain itself automatically at substantially constant temperatures.
- 5 Electric heating units have become very desirable for domestic use in connection with household cook stoves, ovens and also for commercial and scientific use in various forms of heaters, furnaces, ovens, etc. To make such heating units commercially practicable and to adapt them to wide use, it is desirable that the heater be of cheap, economical and rugged construction. It is also very desirable that such heating units be 15 adapted to maintain the heated device at substantially constant temperatures. Substantially constant temperatures in the heated device have heretofore been obtained by the use of suitable supplemental thermostatic control units.
- 20 Resistors embodying a series of contacting carbon blocks, commonly referred to as carbon pile resistors, have been previously proposed for various purposes other than heating. For example, carbon pile resistors have been proposed heretofore in which the inherent negative coefficient of resistance of the carbon unit was compensated for sufficiently to provide a resistor having substantially no change in its resistance over a relatively wide operating range.
- 25 This invention differs fundamentally from the above mentioned types of resistors in that a heating unit is herein proposed, which 30 unit automatically maintains itself at substantially constant temperatures. This insures a substantially constant temperature in the heated medium without the use of supplemental thermostat devices. This result is obtained by providing a heating unit which as a whole has a much larger positive temperature coefficient of resistance than that of any known metallic resistor. Moreover, the resistor portions of a heating unit 35 embodying my invention have a relatively large heat transmitting surface and are ordinarily in heat conducting relation with the object or body to be heated, whereby the heating unit may be operated at temperatures 40 relatively close to that of said heated body. Owing to the very high temperature coefficient of resistance thereof, the resistance of the complete unit increases very rapidly with slight increases in its temperature, thus automatically reducing the energy 45 input to the resistor when the operating temperature of the heating unit increases but slightly. The heating element herein proposed may, therefore, be said to inherently maintain itself at a substantially constant operating temperature as distinguished from previously proposed heating units which operate at materially higher temperatures than the medium being heated and which attempt to maintain a substantially 50 uniform temperature in the heated body through changes in the electric current traversing the resistor effected by the operation of thermostatic devices.
- 55 An object of this invention is to provide a self-controlling electric heating unit having a very high positive temperature coefficient of resistance, whereby the temperature of said unit may be maintained substantially constant within very narrow limits.
- 60 A further object of the invention is to provide a heating unit, the resistor portions of which may be maintained at temperatures but slightly greater than that of the object to be heated, whereby ruggedness and 65 longevity of the heating unit may be readily obtained.
- 65 Another object of my invention is to provide a heating unit adapted to maintain itself within very close limits at predetermined adjusted temperatures.
- 70 A further object of this invention is to provide an electrical heating unit comprising a multi-part resistor of relatively small temperature coefficient of expansion cooperating with a material of relatively high temperature coefficient of expansion so arranged that the heating unit as a whole will have a relatively high positive temperature coefficient of resistance.
- 75 A further object of the invention is to provide an electrical heating unit which will very rapidly heat up to a predetermined desired operating temperature.
- 80 Another object of this invention is to provide an electrical heating unit of simple, rugged and economical construction for use in cook stoves, ovens and other heating devices.
- 85 Other objects of the invention will be apparent to those skilled in the art from the description of it hereinafter given.

Fig. 30 is an enlarged sectional view of a resistor block provided with an electrical insulating shell.

One form of heating unit contemplated by my invention may comprise a series of substantially contacting aligned resistor blocks or bodies disposed adjacent to a confining or cooperating or expansion member adapted to receive heat from said blocks. Said cooperating member preferably has a relatively high temperature coefficient of expansion with respect to that of said blocks, and if electrically conductive, is insulated from said blocks. Electric connections are provided whereby electric energy, preferably at constant voltage, may be passed through said aligned blocks. It may be noted that ordinarily a large proportion of the electric resistance of said series of blocks is due to the contact resistance between adjacent blocks.

Adjustable pressure applying means is provided whereby said blocks may be placed under an adjustable predetermined initial longitudinal pressure. Said pressure applying means cooperates with said cooperating member so that the pressure between the resistor portions will be decreased on expansion of said cooperating member, due to heat received from said resistor blocks, and vice versa. The temperature at which the heating unit is maintained is dependent upon the initial pressure placed upon said blocks by said pressure applying means. In a heating unit as above described, it will be seen that when the series of blocks has substantially attained the desired temperature, a slight further increase in temperature will cause reduction of the mutual pressure between said blocks and hence considerably increase the resistance of the entire series of blocks. Thus I have provided a heating unit which, due to its high temperature coefficient of resistance, is adapted to maintain itself at predetermined temperatures within very close limits.

It may be further mentioned that, on account of the extent and character of contact between the series of resistor blocks and the body to be heated, the temperature of said resistor blocks may be but slightly higher

than that of the heated object, thereby increasing to a very appreciable degree the life of the heating unit and rendering possible a thermostatic control based in part on the 5 temperature of the resistor.

In Figs. 1 and 2 is shown one form of heating unit contemplated by my invention, comprising a container 1, which may be of metal and which preferably has a high 10 temperature coefficient of expansion. Disposed within said container 1 is a series of substantially contacting aligned resistor blocks or bodies 2, which may be composed of any suitable resistor material, such as, for example, compressed graphite. The container 1 is adapted to receive heat from the resistor blocks when said blocks 2 are heated, and is electrically insulated therefrom by suitable insulating means 3, such as vitreous enamel, 15 mica, etc. Electric energy may be supplied to said blocks 2 through conductors 4 and 5, which, in turn, are shown as contacting electrically with the conducting blocks 6 and 7, the electric energy being transmitted 20 through the series of blocks 2 between the conducting blocks 6 and 7. The blocks 6 and 7 assist also in applying pressure to said blocks 2. As will be more readily seen by reference to Fig. 6^a, a threaded spindle 8 is 25 adapted to move through the threaded boss 9. One end of said spindle 8 is operatively connected to the block 7 and insulated therefrom and the other end of the spindle 8 is shown as provided with a knurled head 10. 30 Thus by turning the head 10 the resistor blocks 2 may be compressed between the blocks 6 and 7 to any desired degree. The higher the operating temperature of the heating unit desired, the greater is the initial 35 longitudinal pressure imposed upon said blocks 2.

In Figs. 3 and 4 is shown a heating unit comprising a closed tube 11 in which is disposed a series of substantially contacting 40 aligned circular resistor blocks 12. The end 13 may be suitably affixed to the tube 11 by any suitable means, as by welding. The electric conducting blocks 14 and 15 are preferably similar in cross section to resistor 45 blocks 12, and are similar in construction and function to the blocks 6 and 7 of Fig. 1. Insulating means 3, conductors 4 and 5, spindle 8, boss 9 and knurled head 10 are similar in construction and function to the corresponding members described under Figs. 1 and 2.

In Figs. 7 and 8 is shown another form of heating unit in which a series of apertured resistor blocks 16 is disposed on a rod 17, 50 which is provided with an enlarged portion 18 at one end and a threaded portion 19 at the other end. Conductors 20 and 21 are connected respectively to blocks 22 and 23, whereby electric energy may be readily supplied to the blocks 16. Electric insulation 24

is disposed between the rod 17 and blocks 16, 22 and 23 between the enlarged portion 18 and block 22, and between block 23 and member 26. Pressure may be imposed upon the resistor blocks 16 by turning the nut 25, 55 whereby the pressure is transmitted through the member 26 and block 23 to the resistor blocks 16.

Heaters embodying my invention and arranged in spiral form are advantageous for 70 many purposes since thereby a relatively large heating surface can be arranged in a small space. Thus such heating units might be advantageously employed in domestic stoves for hot plates. In Figs. 13 and 14 is 75 shown a spiral tubular form of heater which, except for its spiral shape, is quite similar in its general characteristics to the heating unit shown in Figs. 3 and 4. Within the spiral tube 27, which is preferably of metal, are 80 shown a series of spirally aligned resistor blocks 28. The blocks 28 as shown are of substantially cylindrical shape with spherically convex ends, whereby the blocks 28 85 may readily contact one with another, regardless of the curvature of the spiral. The blocks 28 are suitably insulated from the metal tube 27 by any suitable insulating means 29. At the inner end of the spiral is 90 shown an electric conductor 30 connected to a fixed conducting block 31, which block 31 is insulated from the tube 27 and against which one of the resistor blocks 28 abuts. At the outer end of the spiral an electric conductor 32 is connected to a conducting block 33 fixedly disposed adjacent the outer end of 95 the spiral 27 but insulated therefrom. Movable through the block 33 is the threaded spindle 34 having a knurled head 35 and provided at its inner end with an enlarged 100 portion 36. By suitably turning the head 35, the resistor blocks 28 may be placed under a predetermined pressure between the movable portion 36 and the stationary block 31. A 105 spiral heater contemplated by my invention 110 may be disposed entirely in one plane as shown in Figs. 13 and 14 or may be disposed in a plurality of planes as in the case of a spiral ascending about a cylindrical space.

In Figs. 17 and 18 is shown another form 115 of spiral heater in which a spiral tubular cavity is formed between the cooperating metal members 37 and 38, which members may be suitably affixed in cooperative relation, as by welding. Within the cavity are 120 shown the spirally aligned resistor blocks 39, which in this case are shown as cylindrical in shape, one end of which being spherically concave and the other end spherically convex, whereby the blocks 39 may 125 readily contact one with another, regardless of the curvature of the spiral. Between the resistor blocks 39 and the members 37 and 38 is disposed suitable electric insulating means (not shown). At the inner end of 130

the spiral is the electric conductor 41, connected to the conductive block 43, which is disposed at the inner end of the spiral cavity and which is also suitably electrically insulated from the portions 37 and 38. At the outer end of the spiral is the electric conductor 43 attached to the conductive block 44, which block is fixedly mounted at the outer end of the spiral cavity and insulated 16 from the sides thereof. Movable through the block 44 is the threaded spindle 45 provided with a knurled head 46 and connected at the inner end thereof by a suitable joint with the member 47 through which pressure 15 may be exerted upon the series of resistor blocks 39.

In Figs. 19 and 20 is shown a form of heating unit somewhat similar to that shown in Figs. 7 and 8 but spiral in form. On the 20 spiral rod 48 is disposed a series of spirally aligned apertured resistor blocks 49. The blocks 49 are shown as being substantially spherical in shape. The rod 48 is provided with a suitable insulating coating 50. At 25 the inner end of this spiral is an electric conductor 51 connected with a conducting block 52 held in position by the enlarged end 53 of the rod 48 and insulated from said rod 48 and said end 53. One of the resistor 30 blocks 49 abuts the block 52. At the outer end of the spiral is an electric conductor 54 which is connected to a conducting block 55. On the outer threaded end of the rod 48 is a knurled nut 56, which is adapted to 35 move the block 55 to thereby place the series of resistor blocks 49 under a predetermined pressure.

In Figs. 9 and 10 a circular form of heater is shown in which a series of circularly aligned resistor blocks 57 is shown as disposed within a circular container 58 and adjacent to and closely following the curvature of the inner or concave wall thereof. Electric insulating means 60 is disposed intermediate the blocks 57 and container 58. Adjacent to one end of said series of blocks is an electric conductor 61 connected to a suitable binding post 62, which, in turn, supports a conducting block 63 in fixed relation 45 adjacent to one end of said series of blocks. Adjacent to the other end of said series is a conductor 64 connected to a binding post 65, which supports in fixed relation a conducting block 66. Movable through the 50 block 66 is a threaded spindle 67 provided at one end with a knurled head 68. The other end of said spindle 67 is connected through a suitable joint to a block 69 adjacent to the other end of the series of resistor blocks. By turning the head 68 any predetermined longitudinal pressure may be 55 imposed on the series of resistor blocks 57.

It will be noted that in this construction a component of the pressure exerted longitudinally on the blocks 57 presses said blocks 60

radially against the inner concave wall of the container 58 with a force proportional to the said longitudinal pressure, whereby transmission of heat from said blocks to said container 58 is facilitated and whereby the 70 blocks are caused to retain the desired aligned position. It will be observed, of course, that a curvature of relatively large radius is sufficient to obtain the above mentioned desirable characteristics. The conductivity of the heat from said blocks to said container is, of course, substantially in proportion to the heat produced by said blocks, so that the temperature difference between the blocks and the container may remain 80 substantially constant regardless of the amount of heat produced.

To illustrate the operation of my invention, a heating unit similar to that shown in Figs. 9 and 10 was operated continuously for 85 about five weeks at definite predetermined temperatures throughout a range from 35 to 275 degrees centigrade. The resistor blocks employed were of graphite and were substantially rectangular in shape, the width of 90 each block between junctions being approximately $\frac{3}{16}$ ". At temperatures of about 100° C. the temperature of the heater was maintained constant within 2° for periods of several hours. At this temperature the voltage 95 drop across each junction between adjacent blocks was substantially $\frac{1}{2}$ volt. At higher temperatures higher voltages may be maintained between the resistor portion. However, the voltage drop across each junction 100 and the voltage across the entire division is preferably maintained at as low a magnitude as possible in order to prevent possible arcing between the resistor portions and, in general to give the best operating results. 105 At the end of the five weeks run, no visible deterioration of the resistor portions was noted. Preferably, during the operation of my heating unit the voltage of the energy supply is maintained substantially constant. 110 It has been found, however, that commercial sources of electric energy have been satisfactory from this standpoint, the device itself compensating for any normal variation in the applied voltage. This feature will be 115 understood from the consideration that a minor change in the voltage of the source of energy to which the heating unit is connected will be partially compensated for by the inherent operation of the resistor. A 120 slight decrease in the applied voltage causes the current flowing through the resistor to decrease and this causes a slight cooling of the resistance unit. The cooling of the resistance unit decreases the resistance as previously explained and thereby causes an increased current to flow.

In Figs. 15 and 16 is shown a form of heating units in which a series of spirally aligned resistor blocks 70 are disposed in 125

cooperative relation with a spiral cooperating member 71. Between the base 72, and the blocks 70 and members 71 is disposed electrical insulation 73. Between the blocks 70 and the spiral member 71 is disposed electrical insulation (not shown). The inner end of the spiral member 71 is fastened to but insulated from the conducting block 74. The outer end of the spiral member 71 is connected to but insulated from the fixed conducting block 75. Conductor 76 is connected to the block 74, and conductor 77 to the block 75. Movable through the block 75 is the threaded spindle 78 provided with a knurled head 79 at one end and connected at the other end through a suitable joint to the block 80. By turning the head 79 a predetermined longitudinal pressure may be applied to the spirally aligned blocks 70. The blocks 70 are shown as having one end of cylindrical concave shape and the other end of cylindrical convex shape, whereby adjacent blocks may readily contact with each other whatever the curvature of the spiral.

In Figs. 11 and 12 is shown a spiral form of heating unit in which spirally aligned resistor blocks 81 are disposed between the fixed blocks 82 and 83, adjustable pressure on the resistor blocks being obtained by moving a spiral cooperating member 84. The member 84 is fixed at its inner end to the block 82 but insulated therefrom. The outer end of the member 84 is affixed to the spindle 85. The resistor blocks 81 are shown as cylindrically convex at one end and cylindrically concave at the other end, whereby said resistor blocks may readily contact one with another regardless of the curvature of the spiral. Connected to the conducting block 82 is the electric conductor 86, and connected to the conducting block 83 is the conductor 87. The blocks 81 and member 84 are electrically insulated from the base 88 by insulation 89. The blocks 81 are insulated from the member 84 by suitable insulation (not shown). Mounted on the base 88 is a member 90 through which is movable a threaded spindle 85, which is provided with a head 91 at one end, and to the other end of which is attached the spiral member 84. By turning the head 91, the length of the spiral 84 between the stationary blocks 82 and 83 may be shortened to thereby impose a predetermined pressure upon the aligned blocks 81.

In Figs. 5 and 6 is shown a modified form of heating unit in which a plurality of resistor particles or bodies are employed. The resistor particles 92, which may be of any suitable shape, are shown as confined within a closed tube 11. The end 13 may be suitable affixed to the tube 11 by any suitable means, as by welding. The blocks 14 and 15 are shown as similar to the corresponding blocks

14 and 15 in Fig. 3. Insulating means 3, conductors 4 and 5, spindle 8, boss 9 and handle 10 are similar in construction and function to the corresponding members described under Figs. 1 and 2. Initial pressure is imposed on the resistor particles 92 by turning the knurled head 10, and thereby causing the block 15 to move toward the block 14.

The resistor blocks adapted to be employed in heating units of my invention may be of various shapes, several forms of which have been discussed in the above description. In Fig. 21 is shown a resistor block 100 of trapezoidal cross-section, such as might be employed in the form of heater unit shown in Fig. 9, although a rectangular form of resistor block 101, as shown in Fig. 23, may also be employed in the heater shown in Fig. 9. The block 101 is of substantially the same shape as that shown in Fig. 1. In Fig. 22 is shown a cylindrical form of resistor block 102 substantially similar to that shown in the heater in Fig. 3. In Fig. 24 is shown a resistor block 93, which may be satisfactorily employed in spiral heater units such as shown in Figs. 11 and 15. The ends of the block 93 are both shown as cylindrically convex, whereby said block may uniformly contact with adjacent resistor blocks regardless of the curvature in a spiral form of heating unit. The resistor block 103 shown in Fig. 25 is provided with one end of cylindrical concave form and the other end of cylindrical convex form, whereby the block 103 may be readily employed in a curved or spiral form of heater, such as, for example, the heater shown in Fig. 15. An apertured spherical form of resistor block 49 is shown in Fig. 26, which is substantially similar to the resistor block employed in the heater shown in Fig. 19. The cylindrical resistor block 104 shown in Fig. 27 is provided with one spherical concave end and one spherical convex end, whereby electrical contact may readily be obtained between the adjacent blocks when employed in a curved or spiral heater. The cylindrical resistor block 94, as shown in Fig. 28, is provided with spherical convex ends and shows in an enlarged form substantially the same form of resistor block shown in Figs. 13 and 14. Resistor blocks provided with curved ends, such as above described, may also be employed, of course, in straight forms of heaters. In Fig. 29 are shown various forms of resistor particles adapted for use in a form of heating unit such as shown in Figs. 5 and 6. The particles 95 are represented as being of irregular shape. However, it may be desired in a heating unit such as shown in Figs. 5 and 6 to employ particles of uniform shape and size. In such case, spherical particles 96 or rectangular particles 97 may be employed.

In Fig. 30 is shown a resistor block 98 provided with an insulating shell 99 which may be of any suitable material, having preferably the same temperature coefficient of expansion as the resistor material. Thus, with a resistor block such as of graphite there may be employed an insulating shell composed of material such as porcelain or aluminum. If a block 98 were employed in a heating unit such as shown in Figs. 13 or 17, other insulation would be unnecessary between the resistor blocks and the walls of the spiral cavity of the heater.

The operation of a heating unit contemplated by my invention may be understood by reference to the construction shown in Figs. 1 and 2. The resistor blocks or bodies 2 are placed under a certain predetermined initial longitudinal pressure between the 20 conducting blocks 6 and 7. The longitudinal pressure through the series of resistor blocks is, of course, exerted in the direction of passage of the current through the blocks, regardless of whether the series of blocks 25 is arranged in straight or curved alignment. The higher the operating temperature desired the greater is the initial pressure imparted to the series of resistor blocks. By connecting the conductors 4 and 5 to a 30 suitable source of alternating or direct current, electric energy, preferably at a constant voltage, is passed through the series of resistor blocks 2. Heat is developed from said electric energy, due in part to the resistance of each block 2 and in part to the contact resistance between adjacent resistor blocks. A portion of the heat generated is 35 transmitted to the container or expansion member 1, which has a relatively large temperature coefficient of expansion with respect to that of the resistor blocks.

The temperature of the heating unit rises to the predetermined temperature, the current meanwhile constantly diminishing at 45 which predetermined temperature the heat generated within the heating unit is equal to the heat dissipated thereby. Thus, considering the operation of the unit when the desired temperature has been reached, further increase in temperature of the container 50 1 decreases the pressure between adjacent resistor blocks and thereby greatly increases the resistance of the series, thus reducing the current and consequently the heat developed. The container 1 is thereby slightly cooled and contracts, thereby appreciably increasing the pressure between adjacent resistor blocks and hence decreasing the resistance of the series. The current is thus 55 increased and also the rate of development of heat, whereby the container 1 is slightly increased in temperature. The above cycle continues during the operation of the heating unit. Thus it will be seen that my heating unit has a very high temperature coeffi-

cient of resistance, greater than that of any known metallic resistor, as a result of which substantially constant temperatures may be maintained with variations of but very small magnitude.

It may be noted that other things being equal, the sensitivity of the heating unit, namely, the closeness of temperature control thereof is proportionate to the distance between the junctions of the resistor portions. Thus, where the resistor blocks are relatively long, the length of the cooperating member is proportionately increased and hence a smaller increase of temperature is necessary to decrease the pressure between adjacent resistor blocks. Thus, the degree of sensitivity desired in a heating unit may be controlled by the size of resistor portions employed, and if it be desired to have the temperature range relatively large this can be secured by using a larger number of resistor blocks per unit of length of the heating unit.

It will thus be noted that my device maintains a substantially constant temperature with the desired degree of sensitivity, which may be varied, for example, by the size and number of resistor blocks, as previously set forth.

Resistor blocks and resistor particles employed in heating units contemplated by my invention may be of any suitable material, preferably of high resistance. Various forms of carbon, including compressed graphite, have been found satisfactory for this purpose. Graphite is particularly advantageous due to its low coefficient of thermal expansion. Although carbon has a negative temperature coefficient of resistance, my invention is not confined to the use of resistor portions of this character. In general, resistor blocks of as high resistance as possible are desirable, as thereby the number of resistor blocks which must be employed in a heating unit for use with electric energy of a given voltage may be greatly reduced.

The cooperating member, support or container employed in heating units embodying my invention have preferably a very high temperature coefficient of expansion with respect to that of the resistor material. Thus iron, copper, brass, aluminum and metals of similar character are very desirable for such use.

The resistor material may be electrically insulated from the container or cooperating member by any suitable means. For example, the cooperating member may be vitreous enameled. This method is very satisfactory, particularly for ferrous members. Mica might also be employed as insulating material. Furthermore, resistor blocks may themselves be provided with an insulating coating such as shown in Fig. 31.

Such resistor blocks are advantageous where the cooperating member is of a material not readily vitreous enameled, such as, for example, copper, brass or aluminum.

5 It will thus be seen that I have provided a heating unit which is adapted to maintain itself automatically at substantially constant temperatures.

10 It will further be noted that I have provided a heating unit of relatively simple and substantial construction and of very high temperature coefficient of resistance.

15 It will moreover be seen that I have provided an electrical heating unit which will very rapidly heat up to a predetermined desired operating temperature and which will maintain itself at the operating temperature with the desired sensitivity.

20 Furthermore, it is to be understood that the particular forms of apparatus shown and described, and the particular procedure set forth, are presented for purposes of explanation and illustration and that various 25 modifications of said apparatus and procedure can be made without departing from my invention as defined in the appended claims.

What I claim is:

1. In an electrical heating unit adapted 30 to maintain substantially constant temperatures, in combination, a plurality of electrically conductive resistor bodies, confining means disposed in electrical insulating and heat receiving relation to said resistor bodies 35 and adapted to place said bodies under a predetermined initial pressure, said confining means being adapted to vary the pressure between said resistor bodies inversely with the variation in temperature of said 40 confining means.

2. In an electrical heating unit adapted to maintain substantially constant temperatures, in combination, a plurality of electrically conductive resistor bodies, means of 45 relatively high temperature coefficient of expansion confining said resistor bodies, and means for passing current through said resistor bodies, whereby said bodies may be heated and may maintain said confining 50 means at substantially constant predetermined temperatures.

3. In an electrical heating unit adapted to maintain substantially constant temperatures, in combination, a plurality of electrically conductive resistor bodies, a confining means of relatively high temperature coefficient of expansion adapted to confine said resistor bodies and to receive heat therefrom, means associated with said confining means 60 to apply a predetermined pressure to said resistor bodies, and means for passing electric current through said resistor bodies, whereby said bodies may be heated to maintain said confining means at substantially constant predetermined temperatures.

4. An electrical heating unit comprising a plurality of substantially aligned electrically conductive resistor portions, a confining means disposed in electrically insulating and heat receiving relation to said resistor portions and adapted to place said portions under a predetermined initial pressure and to maintain said portions in aligned relation, adjustable means to vary said initial pressure, and means for passing current 75 through said resistor portions.

5. An electrical heating unit comprising a plurality of substantially aligned electrically conductive resistor blocks, a confining means adapted to place said blocks in 80 aligned relation under a predetermined initial pressure, adjustable means to vary said initial pressure, and means for passing current through said resistor blocks, whereby said confining means may be maintained at 85 substantially constant predetermined temperatures.

6. In an electric heating unit adapted to maintain itself at substantially constant temperatures, in combination, a series of substantially contacting aligned resistor blocks, 90 a member having a relatively high temperature coefficient of expansion with respect to that of said blocks disposed in cooperative relation to said blocks and adapted to 95 receive heat therefrom, means for electrically insulating said member from said blocks, means for supplying electric energy to said aligned blocks, and means for placing said blocks under a predetermined initial longitudinal 100 pressure variable with the expansion and contraction of said member due to heat received from said resistor blocks.

7. In an electric heating unit adapted to maintain itself at substantially constant 105 temperatures, in combination, a series of substantially contacting aligned resistor blocks, a support for said blocks having a relatively high temperature coefficient of expansion with respect to that of said blocks, 110 said support being adapted to receive heat from said blocks, electrical insulating means disposed between the electrically conductive portions of said blocks and said support, electrical conductors connected to the ends 115 of said series of blocks whereby electric current may be passed through said blocks, and cooperative means acting on the ends of said series of blocks adapted to place said blocks under a predetermined initial longitudinal 120 pressure variable with the expansion and contraction of said support due to heat received from said resistor blocks.

8. In an electric heating unit adapted to maintain itself at substantially constant temperatures, in combination, a series of substantially contacting aligned resistor blocks, a support for said blocks having a relatively high temperature coefficient of expansion 125 with respect to that of said blocks, disposed 130

electrical insulating relation to said blocks, 5 said support being adapted to receive heat from said blocks, electrical conductors connected to the ends of said series of blocks whereby electric current may be passed through said blocks, a member disposed at one end of said series of blocks cooperating with an adjacent portion of said support to form a stop for further movement of said blocks towards said member, and adjustable means disposed adjacent the other end of said series of blocks, cooperating with an adjacent portion of said support and adapted to apply a predetermined initial longitudinal pressure to said blocks variable with the expansion and contraction of said support due to heat received from said resistor blocks.

9. In an electric heating unit adapted to 20 maintain itself at substantially constant temperatures, in combination, a series of substantially contacting spirally aligned resistor blocks, a container comprising a pair of cooperating metal members adapted to substantially enclose said blocks and maintain said blocks in said spirally aligned relation and having a relatively high temperature coefficient of expansion with respect to that of said blocks, electrical insulating means disposed between the electrically conductive portions of said blocks and said support, electrical conductors connected to the ends of said series of blocks whereby electric current may be passed through said blocks, 30 a member disposed at one end of said series of blocks cooperating with an adjacent portion of said support to form a stop for further movement of said blocks towards said member, and adjustable means disposed adjacent the other end of said series of blocks cooperating with an adjacent portion of said support and adapted to apply a predetermined initial longitudinal pressure to said blocks variable with the expansion and contraction of said support due to heat received from said resistor blocks.

10. In an electric heater unit adapted to maintain itself at substantially constant temperatures, in combination, a container of 50 relatively high temperature coefficient of expansion, a plurality of resistor particles of relatively low temperature coefficient of expansion as compared with that of said container disposed in substantially contacting relation and in close confinement within said container, said container being adapted to receive heat from said resistor particles, electrical insulating means disposed between said particles and said container, electrical conductors disposed adjacent to said resistor particles whereby electric current may be passed through said particles, and cooperative means adapted to place said particles under a predetermined pressure variable 60 with the expansion and contraction of said

container due to heat received from said resistor particles.

11. In an electric heating unit adapted to maintain itself at substantially constant temperatures, in combination, a series of substantially contacting aligned carbonaceous resistor blocks, a metal container for said blocks adapted to maintain said blocks in said aligned relation and having a relatively high temperature coefficient of expansion with respect to that of said blocks, said container being adapted to receive heat from said blocks, electrical insulating means disposed between the electrically conductive portions of said blocks and said container, electrical conductors connected to the ends of said series of blocks whereby electric current may be passed through said blocks, and cooperative means acting on the ends of said series of blocks adapted to place said blocks under a predetermined initial longitudinal pressure variable with the expansion and contraction of said container due to heat received from said resistor blocks.

12. In an electric heating unit adapted to 90 maintain itself at substantially constant temperatures, in combination, a series of resistor blocks having curved ends, at least one end of each block being convexly curved, said blocks being arranged in substantially 95 contacting curved alignment, a support for said blocks having a relatively high temperature coefficient of expansion with respect to that of said blocks, said support being adapted to receive heat from said 100 blocks, electrical insulation disposed on said blocks adjacent said support, whereby said support is electrically insulated from said blocks, electrical conductors connected to the ends of said series of blocks whereby 105 electric current may be passed through said blocks, and cooperative means acting on the ends of said series of blocks adapted to place said blocks under a predetermined initial longitudinal pressure variable with the 110 expansion and contraction of said support due to heat received from said resistor blocks.

13. In an electric heating unit, in combination, a series of aligned graphite resistor blocks, an expansion member cooperating with said blocks along the linear extent thereof and arranged to receive heat therefrom and having a relatively high temperature coefficient of expansion with respect to that of said blocks, electrical insulating means disposed between said graphite blocks and said expansion member, means for passing electric current through said series of blocks to heat said blocks, and means to place said blocks under a predetermined initial pressure longitudinally of said series of blocks variable with the expansion and contraction of said expansion member due to heat received from said resistor blocks. 130

14. In an electrical heating unit, in combination, a substantially curved expansion member, a series of aligned resistor blocks disposed closely adjacent said expansion member on the concave side thereof and closely following the concave curvature thereof, said expansion member having a relatively high temperature coefficient of expansion with respect to that of said blocks and being arranged to receive heat from said blocks, said blocks being electrically insulated from said expansion member, means for placing said blocks under a predeter-

mined initial pressure longitudinally of said series of blocks, whereby a component of said longitudinal pressure presses said blocks against said expansion member with a force proportional to said longitudinal pressure, said longitudinal pressure being variable with the expansion and contraction of said expansion member due to heat received from said resistor blocks, and means for passing electric current through said series of blocks to heat said blocks.

In testimony whereof I affix my signature.

STERNE MORSE.
